SAFETY RAZOR

Fritz Philip Steinhauer, Chicago, Ill.

Application December 21, 1942, Serial No. 469,653

4 Claims. (Cl. 30—70)

This invention relates to safety razors in which a thin centrally apertured blade having two or more cutting or shaving edges is firmly held between two clamping members so co-ordinated, one with respect to the other, that the cutting edges come properly positioned in relation to the guarding safety surfaces of said members; and that the blade is transversely flexed to give the cutting edges a shearing rake or angle with respect to the beard hairs to thus provide efficient, painless and safe shaving. It is of utmost importance to so position the cutting edges of the blade in relation to the guarding surfaces of the holding or clamping members that the cutting edge shears off, so to speak, the beard bristles instead of scraping them off like a hoe would weeds; my safety razor will shave and shear close, without scratching or cutting the skin of the face, be this wrinkled or plump or even blessed with sharp-cornered jaw bones.

Another one of the important improvements in my safety razor is the provision of a simple and efficient means for re-sharpening, stropping, the cutting edges of the blade; this means resides in the novel two-part clamping member more fully described hereafter.

The above as well as other novel features of my invention will be best understood from the following description of a preferred embodiment thereof selected for illustration and shown in the accompanying drawings, in which—

Fig. 1 is a top plan view of my improved razor; Fig. 2 is a similar view with clamping part of the two-part blade clamping member removed; Fig. 3 is a top plan view of the cheek guard member;

Fig. 4 is a detail view of the cutting face, the front, of my safety razor;

Fig. 5 is a detail sectional view on line 5—5 of Fig. 1;

Fig. 6 is a detail sectional view on line 6—6 of Fig. 4;

Fig. 7 is an end elevation showing the method of stropping or honing the cutting edge of the blade;

Fig. 8 is a perspective view of parts of the two-part flexing and clamping member, and

Fig. 9 is a perspective view of parts of another form of the two-part flexing and clamping member.

Similar numerals indicate corresponding parts in the several views.

Numeral 1 indicates the handle, numeral 2 indicates the blade supporting and cheek guard member, 3 the blade, 4 the clamp part and 5 the

blade flexing or forming and positioning part of the two-part clamping member. The blade supporting plate or cheek guard 2 is provided with a central aperture 12 and a centrally located lateral depression 7 and also with lateral apertures 6 located near the outer inwardly curved edges of the cheek guard; the hole 12 permits the threaded projection 8 of clamp 4 to pass through and the lateral depression 7 admits, in 10 snug fit, the lateral projection 16 of 5, shown in Fig. 5, to properly position the two-part clamping member on the cheek guard member; the elongated lateral apertures 6 of the part 2 are located near the cheek guarding surfaces just a 15 little beyond, inwardly, the cutting edge of the blade where the part 2 is slightly recessed to provide escape room for the lather and the bits of beard cut off, the lateral apertures 6 provide egress for the lather which then collects in the 20 in-curved lips of the cheek guard thus preventing the lather from splattering; the thus gathered lather can be readily washed out under a faucet or in a bowl of water; the clamp part 4 is provided with positioning projections 14 dimensioned 25 and positioned to fit depressions 15 in part 5, the flexing part of the two-part member.

The two-part flexing and clamping member comprises the part 4 and part 5; the blade flexing and firming face 17 of the part 5 is slightly concaved transversely and to such degree that the thin flexible razor blade will, when firmly clamped on the cheek guard member, become so flexed that the most effective rake or angle of the plane of the cutting edge to the hairs of the beard is obtained; also, the cutting edge becomes positioned in the most efficient relation to the guarding surfaces on 2 and 5 for safe, good shaving. The ideal angle or rake mentioned above would be when the imaginable plane of the cutting edge 30 was at right angle, 90 degrees, to bristles of the beard; in practice we cannot attain that ideal condition, but the nearer we can or do approach it the better and closer and least painful shaving we get; in my razor that ideal condition is approached to highest degree possible in actual 35 practice.

In Fig. 8 are shown the parts 4 and 5 of one form of the two-part clamping and flexing member; the part 5 is provided with a laterally concaved flexing face 17 and with lateral centrally located depressions 15 and directly under these are the lateral projections 16, shown in Fig. 5, and a central aperture 21; the part 4 is provided with a central threaded projection 8 and centrally located lateral projections 14; projection 8

is adapted to pass through hole 21 and the projections 14 are adapted to engage in depressions 15; the lateral projections 16 of part 5 are adapted to snugly engage in lateral depressions 7 of the cheek guard 2.

Fig. 9 shows a modified form of the two-part clamping and flexing member; in this form the part 51 is provided with the laterally concaved flexing faces 10 and parallel grooves or channels 9; the part 41 is provided with a central threaded projection 8 and with parallel tongues or projections 11 so dimensioned and disposed that they slidably fit into and engage in the grooves 9; when the two parts, 41 and 51, are thus assembled they form the two-part clamping and flexing member; the part 41 is provided with lateral centrally located projections 14 which are adapted to snugly engage in the depressions 7 of the cheek guard 2.

To assemble the razor, the parts 4 and 5, Fig. 8, are assembled together, then held level, the centrally apertured blade is then put on over the projections 8 and 16, the cheek guard plate 2 is then put on in such way that the depression 7 admits and engages the projections 16 of part 5 and the handle is then screwed onto the threaded projection 8 until tight, the blade will then become properly flexed and positioned and the cutting edges of the blade will be in the most efficient shaving relation to the skin guarding surfaces of the blade holding members 2 and 5. Fig. 6 gives a sectional view of the assembled razor.

In my improved construction of the safety razor the cutting edge of the flexible blade is so positioned, by the co-operative locating and flexing actions of the clamping guard 5 with the holding guard 2, that the much desired shearing—instead of scraping—condition is obtained in the highest degree possible in practice; notwithstanding this, there still remains some slight tendency for the cutting edge to bend back, ruffle, at spots where some stiff bristles of the beard are encountered; such bending back or ruffling may be minute in degree, even microscopic, still the spot on the cutting edge that is ruffled, bent back, does not and cannot shear cut as do the perfectly straight parts of the cutting edge, the shearing angle of the ruffled, bent back spots has been changed, away from the approximately right angle to the beard.

As one of the features of my invention I provide means for re-aligning the ruffled spots on the cutting edges; the clamp part 4 is so constructed and proportioned that when the flexing part 5 is removed from it and the blade is then clamped to the blade supporting guard 2 by the clamp 4 alone the blade will be held in a straight position, as shown in Fig. 7, and its cutting edges will be in proper angular relation to the upper face of part 4 for stropping or sharpening. By stroking the razor, so assembled, over surface of a plate glass mirror any ruffling on the edge of the blade, before referred to, will become re-aligned with the rest of the cutting edge. Also, the blade may be honed and stropped when it is clamped straight as above described, first one side of the edges and then the other by reversing the blade. When the two-part flexing and clamping member shown in Fig. 9 is used in the razor combination the flexing part 51 is removed from the clamp part 41 and the part 41 alone is used to clamp the blade in straight

position on the cheek guard 2 for stropping or sharpening; the upper corners of the lateral tongues 11 of part 41 are so proportioned and positioned that the proper angular relation for stropping is obtained.

It will be observed that the clamp 4, or the clamp 41, when used alone will not flex the blade but will hold it straight on the guard member 2; the lower lateral edges of clamp 4 do not extend beyond the blade fulcrum edges of the guard 2; it is only when the flexing cap part 5 is assembled with the clamp 4 and this assembly is used for clamping the blade that flexing, forming, is obtained; the lower edges that are the ends of the flexing face 17 of part 5 extend beyond the blade supporting fulcrums of the guard 2, the distance that these edges extend beyond the fulcrum edges and the curvature of the flexing surfaces are so organized, proportioned, that the cutting edges of the blade are positioned in the most efficient relation to the guard surfaces on 2 and 5 adjacent to the cutting edges.

I have illustrated and described the preferred construction of my invention; various modifications may be made without departing from the advantages in and the scope of the invention pointed out. For one example, the lateral tongues of the clamp 41 may be made bevel shape instead of the rectangular shape shown and the engaging lateral grooves in part 51 also being made bevel shape to fit the bevel tongues.

I claim:

1. A safety razor comprising a centrally apertured flexible blade, a blade supporting cheek guard member, a two-part clamping member, said two parts having tongue and groove engagement with each other and provided with lateral centrally located projections for positioning the blade on the cheek guard member, and means for securing the clamping member to the cheek guard member.

2. A safety razor comprising a centrally apertured flexible blade, a blade supporting cheek guard member having a lateral centrally located groove and a centrally located aperture, a two-part clamping member having lateral centrally located projections and a centrally located round threaded projection, said projections adapted to position the blade on the cheek guard member, and a handle having threads at one end to engage said threaded projection to firmly clamp the blade in shaving relation on the cheek guard member.

3. A safety razor structure comprising a centrally apertured flexible blade, a blade supporting cheek guard member having a lateral centrally located groove and a centrally located aperture, a clamping member having lateral centrally located projections adapted to pass through the aperture in the blade and to engage in the groove of the cheek guard member, and means for firmly securing the clamp member to the cheek guard member to hold the blade in straight position.

4. A safety razor structure comprising a centrally apertured flexible blade, a blade supporting cheek guard member, a two-part clamping member having means for positioning the blade on the cheek guard member and means for firmly securing the blade to said cheek guard member, the two parts of said two-part clamping member having tongue and groove engagement with each other and being separable.

product having a pH value between the neutral point and the normal pH value of purified corn starch, eliminating impurities and filtering the starch magma and heating and roasting the product to dry the same and convert the same to dextrine.

7. The method of making dextrine which consists in mixing and reacting starch with an oxidizing agent which renders the starch and renders the same capable of accelerated conversion, the said tendered starch being a reaction product of the starch and said agent, incorporating with the mixture an alkali medium producing thereby a reaction starch product having a pH value between the neutral point and the normal pH value of purified starch, and thereafter heating and

roasting the product to dry the same and convert the same to dextrine.

8. The method of making dextrine which consists in mixing and reacting starch milk with an oxidizing agent which renders the starch and renders the same capable of accelerated conversion, the said tendered starch being a reaction product of the starch and said oxidizing agent, incorporating with the mixture an alkali medium producing thereby a reaction starch product having a pH value of about 6.5, filtering the starch magma, and thereafter heating and roasting the product to dry the same and convert the same to dextrine.
